[57] CLAIM

The ornamental design for a dental flosser and pick combination, as shown and described.

DESCRIPTION

FIG. 1 is a perspective view of a dental flosser and pick combination showing my new design;

FIG. 2 is a front elevational view thereof;

FIG. 3 is a top plan view thereof;

FIG. 4 is a right side elevation of FIG. 2; the left side elevational view is a mirror image of the right side elevation;

FIG. 5 is a rear elevational view thereof; and,

FIG. 6 is a bottom plan view thereof.
